UNITED STATES PATENT OFFICE.

EDWARD F. STEELE, OF TERRE HAUTE, INDIANA.

CIGAR AND CIGARETTE HOLDER AND STUB-EJECTOR.

1,313,132.

Specification of Letters Patent. Patented Aug. 12, 1919.

Application filed February 6, 1918. Serial No. 215,646.

To all whom it may concern:

Be it known that I, EDWARD F. STEELE, a citizen of the United States, residing at Terre Haute, in the county of Vigo and State 5 of Indiana, have invented certain new and useful Improvements in Cigar and Cigarette Holders and Stub-Ejectors; and I do hereby declare the following to be a full, clear, and exact description of the invention, 10 such as will enable others skilled in the art to which it appertains to make and use the same.

My invention relates to combined cigar and cigarette holders and stub ejectors and 15 is equipped with a novel sliding ejector which is positioned within the bowl end of the holder so that the stubs of the cigars or cigarettes located in the bowl may be readily and quickly ejected therefrom. 20 Another object of my invention is to provide a combined holder and stub ejector in which the ejector plate is slidably mounted in the bowl end of the holder and may be readily manipulated so as to throw or eject 25 the stubs of cigars or cigarettes from the bowl.

A further object of this invention is to provide a combined holder and stub ejector of this character which will be simple, practical and comparatively inexpensive in construction and one that can be manufactured and sold at a low cost.

With these and other objects in view, the invention consists in the novel combination 35 and arrangement of parts hereinafter more fully described and set forth in the claim hereto appended.

In the drawing:

Figure 1 is a side elevation of a cigar 40 holder and ejector as made in accordance with this invention.

Fig. 2 is a vertical longitudinal sectional view taken on the line 2-2 of Fig. 1.

Fig. 3 is an end view of the holder and 45 ejector.

Fig. 4 is a perspective view of the ejector plate.

Fig. 5 is a side elevation of a slightly modified form of the invention.

Fig. 6 is an end view of the modified form 50 of the invention.

Like numerals of reference designate corresponding parts in all the figures of the drawing.

Referring to the drawing, the numeral 55 indicates a cigar holder and stub ejector in its entirety, and it comprises the usual tapered body 6, the smaller end of which constitutes a mouth piece 7. The enlarged end of the body is provided with an inwardly extending socket 8 which constitutes a cigar or cigarette receiving bowl. The body is provided centrally with a longitudinally extending passage or bore 9 which communicates with the socket 6 to permit 60 smoke to be drawn from the cigar or cigarette positioned in the socket into the mouth of the user. The wall of the socket is provided with a longitudinally extending recess 10 which has its side walls grooved as indicated at 11 to receive the ejector plate 12. The bottom wall of the slot or recess 11 is provided with a longitudinally extending slot 13 which terminates adjacent the rear and front walls thereof. The ejector plate 75 12 is constructed of suitable metal or other material suitable for the purpose and is substantially concavo-convex in cross section. This plate is positioned in the recess 10 and located under the walls 11 so as to freely 80 slide therein. The inner end of said plate is reduced and bent upwardly to provide a stop or cigar stub engaging member 14. The under side of the plate 12 or convex surface thereof is provided centrally with a depending manipulating finger or lug 15 located adjacent the stop engaging end. The lug 15 is adapted to be slidably mounted in the slot 13 and extended beyond the surface of the exterior wall of the body. 90

It is to be understood that the form shown in Fig. 5 is identical in construction with that shown in Figs. 1, 2 and 3, other than being on a reduced scale so as to permit it to be used for cigarettes entirely. 95

Having thus described my invention what I claim is:

A cigar and cigarette holder including a

body having a socket and a longitudinally extending slot in one side wall of the socket, the longitudinal sides of said slot being provided with grooves, an ejector plate disposed below the inner surface of the socket and having its longitudinal edge portions slidably mounted in said grooves, an ejector finger carried by the rear end of said ejector plate, and a manipulating element carried

by the outer side of said plate and exposed 10 exteriorly of the body and extending at right angles thereto.

In testimony whereof I affix my signature in presence of two witnesses.

EDWARD F. STEELE.
